DOUBLE CUTTER HAIR CLIPPER

Joseph Cromonic, Brooklyn, N. Y.

Application September 25, 1945, Serial No. 618,512

9 Claims. (Cl. 30—223)

1

This invention relates to new and useful improvements in a hair clipper, and more particularly to an electrically operated hair clipper.

More specifically, the present invention proposes the construction of a hair clipper having a comb blade having teeth along two opposite edges, the teeth along one edge being finer than the teeth along the other edge and the blade being pivotally mounted so that it may be rotated to bring either set of teeth into operation.

A further object is to provide a hair clipper as aforesaid having improved latch means for fastening the clipping mechanism to the holder therefor.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side view of a hair clipper constructed in accordance with this invention, the electric cord thereof being shown foreshortened.

Fig. 2 is a plan view of the clipper.

Fig. 3 is an enlarged section on the line 3—3 of Fig. 2, parts being indicated in dot-dash lines.

Fig. 4 is an enlarged perspective view of the latch mechanism of the clipper, the handle being shown fragmentally.

Fig. 5 is an enlarged inside view of the clipping mechanism.

Fig. 6 is an enlarged perspective view of the comb blade of the clipper.

Fig. 7 is a section on the line 7—7 of Fig. 6.

Fig. 8 is an enlarged section, showing the cutting blade and comb blade superposed, the alternate position of the cutting blade being indicated in dot-dash lines.

Fig. 9 is an enlarged perspective view of the cutting blade.

Fig. 10 is an enlarged perspective view of the cutter blade support plate of the clipper.

Fig. 11 is an enlarged perspective view of the latch part of the cutting mechanism.

The hair clipper, according to this invention, comprises a body or handle 10 having mounted thereon at one end a hood 10' which carries a vibrator 11 actuated by the usual electric vibrator motor (not shown) to which current is fed by the electric cord 12. The body has an inclined end face 13 to which is secured a latch part 14.

Latch part 14 is best shown in Fig. 4; with which view the dot and dash showings of Fig. 3

should be compared. It includes a hook part 15 secured to the body as by screws 16 such hook providing a socket. Lateral wings 17 stand out from part 15. The forward end of part 15 is integral with a shoulder 18 and thereabove a part 19 terminating at its forward end in an angular flange 20 spaced from the vibrator 11 as indicated at 21 in Fig. 4.

The remainder of the clipper constitutes the clipping mechanism, which is adapted to snap on the latch part 14 and to be thereby held to the body. It includes a support plate 22, see Figs. 3 and 10. This plate has two spaced apertures 23 and 24. The front end of the plate 22 is bent to form a groove 25, there being a front flange 26 and a tension lip 27 integral therewith. The groove 25 forms the forward side of a laterally extending guideway for the cutter blade hereinafter described. Rearwardly of the flange 26 are side bars 28 formed along parts of their lengths by reversely bent portions of the plate 22, thus providing a pair of recesses 29 which provide more tension, the plate 22 being cut out to provide a central opening 30, thereby to establish the side bars 28.

A comb blade 31, best shown in Fig. 6, is secured to the plate 22 by a bolt 32 passing through an aperture 33 in the blade 31 and through the aperture 23 in the plate 22 and also through an aperture in another member overlying the plate 22 and to be described in a moment. As shown in Fig. 3, the head of the bolt is countersunk in the blade and a nut secures the plate and blade together.

The comb blade 31 has, along two opposed edges, a row of fine teeth 34 and a row of coarse teeth 35. "Course" is used to mean wider and thicker in depth. Running parallel with the rows of teeth and outwardly of the aperture 33 are grooves 36. Between the grooves 36 and on opposite sides of the aperture 33 are two recesses 37.

When the comb blade and support plate are superposed, the tension lip 27 is spaced from the blade. A cutter blade 38, best shown in Fig. 9, is for endwise reciprocation in the slideway above mentioned, and which slideway as aforesaid has its front side provided by the groove 25. This slideway, as seen in Fig. 3, is between the comb blade 31 and the support plate 22. The cutter blade 38 has a socket 39 for receiving the end of the vibrator 11, whereupon the vibrator can reciprocate the cutter blade back and forth rapidly in the slideway including the groove 25. The vibrator also retains the cutter blade in place.

The cutter blade has a row of teeth 40 for co-

acting with the forwardly disposed row of comb blade teeth. It also has a track 41, such track interrupted intermediate its end to provide the socket 39; said track fitting in the groove 25. There is a surface 42 on the cutter blade ahead of the track 41 against which the tension lip 27 bears lightly. The ends of this surface 42 are obliquely notched at 43, in line with the tension lip 27 so that at each limit of movement of the cutter blade 38 one end or the other of the lip 27 will have adjacent thereto one of the notches 36 of the cutter blade.

A cutting mechanism latch part 44, best shown in Fig. 11, with which Fig. 3 should be compared, is secured to the support plate by means of a bolt 45 passing through the aperture 24 in the plate 22 (Fig. 10), and through a matching aperture in the latch part 44; as best seen in Fig. 3, where said latch part is shown as the above referred to member which overlies the plate 22 and through which passes the bolt 32 also going through the aperture 23 in the plate 22 and the aperture 33 in the comb blade 31. The bolt 45 is so located that its head may be nested in one or the other of the grooves 33 in the top of the comb blade 31. This latch part is made of a single sheet of metal bent back on itself to form a rearwardly disposed tongue 46. It also has an upwardly extending tongue 47 at its front end which is flexible, due to the flexible nature of the metal. Wings 48 extend rearwardly from an upstanding lateral wall portion 47' which at its top carries the tongue 47, so placed as to engage the opposite side edges of the flange 20 when the parts are assembled as shown in Fig. 3.

On the latch part 44, forwardly of the tongue 47 is a widely extended lateral strip 49 having upwardly extending spring-like lugs or tabs 50 at its ends and, at the juncture of the strip 49 and tabs 50, downward projections 51. When this latch part 44 is tightly secured to the plate 22, the projections 51 lie laterally outward of the plate 22 and fit in the recesses 37 of the comb blade to hold it from wobbling. The strip 49 has an aperture 52 through which the bolt 32 passes, further securing the latch part 44 to the comb blade 31 and the plate 22.

The hood 10", without the cutting mechanism, is clearly shown in Fig. 4, and the cutting mechanism, without the hood, is clearly shown in Fig. 5. When the parts of Figs. 4 and 5 are latched together, the outer faces of the tabs 50 engage opposite exterior surfaces of the hood 10", for positioning the part 44 relative to the hood.

To assemble, the latch part 14 (connected to the handle 13 by the screws 16 as seen in Fig. 4) and the latch part 44 of the cutting mechanism, and now assuming the parts to be arranged as in Fig. 3, the tongue 48 of the latch part 44 is connected with the hook 15 of the latch part 14, and so as to bring the inclined flange 20 of the latch part 14 above the tongue 47 of the latch part 44. Then a slight pressure is exerted, causing said flange 20 to slip downwardly along the rear face of the tongue 47 to snap into engagement with the latter as shown in Fig. 3, thus locking the cutting mechanism with the holder, with the vibrator 11 in the recess or socket 39. To disassemble the cutting mechanism, it is merely necessary to sharply pull it away from the holder, causing the tongue 47 to snap-free of the flange 20.

Assuming that the fine teeth are in active position and that it is desired to employ the coarse teeth of the comb blade, all that is necessary is to lift tabs 50 at the exterior of the hood 10" as

shown in Fig. 1, thereby to lift the projections 51 out of the recesses 37 in the top of the comb blade 31, and turn the comb blade using bolt 32 as a fulcrum. To provide finger-grip aids near the tops of the tabs 50, their upper ends are bent over outwardly and then down to establish outwardly projected enlargements 50'.

When turning the comb blade about the bolt 32, the fingers are placed on the sides of the comb blade at right angles to the teeth thereon. In order to safeguard the fingers from being cut by the cutter blade during this turning, the comb blade is provided with lateral guard flanges 53, see Fig. 2.

15 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

25 1. A hair clipper comprising a body, a vibrator in said body, a latch part secured to said body, and a cutting mechanism having a latch part for coacting with said body latch part to removably secure said cutting mechanism to said body, said cutting mechanism further having a support plate secured to said latch part, a comb blade pivoted to said support plate, and a tension-held cutting blade slidable on said comb blade and having a part coacting with said vibrator for reciprocation of said cutting blade, said comb having, along two opposite edges, rows of teeth, one row of teeth having more teeth than the other row.

30 2. A hair clipper comprising a body, a vibrator in said body, a latch part secured to said body, and a cutting mechanism having a latch part for coacting with said body latch part to removably secure said cutting mechanism to said body, said cutting mechanism further having a support plate secured to said latch part, a comb blade pivoted to said support plate, and a tension-held cutting blade slidable on said comb blade and having a part coacting with said vibrator for reciprocation of said cutting blade, said comb having, along two opposite edges, rows of teeth, one row of teeth having more teeth than the other row, said body latch part having a socket at one end and an inclined flange at the other end, and said cutting mechanism latch part having a tongue fitting in said socket and a springy tongue adapted to slide over said inclined flange and hook therebeneath.

35 3. A hair clipper comprising a body, a vibrator in said body, a latch part secured to said body, and a cutting mechanism having a latch part for coacting with said body latch part to removably secure said cutting mechanism to said body, said cutting mechanism latch part including a strip traversing said cutting mechanism and having spaced outwardly projecting lugs, a support plate secured to said mechanism latch part and having a groove, a comb blade pivotally connected to said support plate, and a cutting blade slidable in said groove and resting on the inner face of said comb blade, said cutting blade having a part coacting with said vibrator for reciprocation of said cutting blade relative to said comb blade, said comb blade having, along two opposite edges, rows of teeth, one row of teeth having more teeth than the other row.

40 4. A hair clipper comprising a body, a vibrator

in said body, a latch part secured to said body, and a cutting mechanism having a latch part for coacting with said body latch part to removably secure said cutting mechanism to said body, a support plate secured to said mechanism latch part and having a groove, a comb blade pivotally connected to said support plate, and a cutting blade slidably in said groove and resting on the top of said comb blade, said cutting blade having an upstanding part constituting a track, said comb blade having, along two opposite edges, rows of teeth, one row of teeth having more teeth than the other row, said support plate having an upstanding transverse wall spaced rearwardly from said groove, said wall and said groove being so shaped and arranged as to constitute the front and rear elements of a slideway for coacting with said track, said support plate having ahead of said groove a down-turned lip slidably engaging the top of said cutting blade ahead of its track, said track being interrupted to provide a socket for receiving a cutter-blade-actuating part of said vibrator, said support plate including a generally horizontal wall portion connecting said upstanding wall and the part of the support plate which carries said groove, said horizontal wall portion having an opening, said actuating part extending through said opening into said socket, said opening affording a field of operation for said actuating part.

5. A hair clipper comprising a body, a hood on said body, a vibrator in said hood, a latch part in said hood secured to said body, and a cutting mechanism having a latch part for coacting with said body latch part to removably secure said cutting mechanism to said body, said mechanism latch part including a strip traversing said cutting mechanism, a support plate secured to said mechanism latch part and having a groove, a comb blade pivotally connected to said support plate, and a cutting blade slidably in said groove and resting on the top of said comb blade, said cutting blade having a part coacting with said vibrator for reciprocation of said cutting blade relative to said comb blade, said comb blade having, along two opposite edges, rows of teeth, one row of teeth having more teeth than the other row, said strip having end flanges overlapping the side walls of said body, said strip at opposite ends having upstanding tabs for engaging oppositely located side surfaces at the exterior of said hood when said two latch parts are coupled.

6. An electric hair clipper comprising a body, an electrically driven vibrator in said body, a latch part secured to said body, a cutting mechanism including a latch part coactive with said body latch part to removably secure said cutting mechanism to said body, a comb blade having, along opposite edges thereof, two different sets of teeth, a cutting blade mounted on said comb blade and having a part coacting with said vibrator for reciprocating said cutting blade, and a support plate connecting said cutting mechanism latch part, comb blade and cutting blade, said comb blade being pivotally connected to said plate so that it can be turned to bring either of its rows of teeth into coaction with said cutting blade, said comb blade being flat at its outer face between said rows of teeth, and inclined at said teeth, and said comb blade having lateral protecting flanges beyond opposite ends of and at right angles to each of its rows of teeth.

7. A hair clipper comprising a body, a vibrator in said body having an activating part, a latch part secured to said body, and a cutting mechanism having a latch part for coacting with said body latch part to removably secure said cutting mechanism to said body, a support plate secured to said mechanism latch part and having a groove, a comb blade pivotally connected to said support plate, and a cutting blade slidably in said groove and resting on the inner face of said comb blade, said cutting blade having an upstanding part constituting a track, said comb blade having, along two opposite edges, rows of teeth, one row

of teeth having more teeth than the other row, said support plate having an upstanding transverse wall spaced rearwardly from said groove, said wall and said groove being so shaped and arranged as to constitute the front and rear elements of a slideway for coacting with said track, said support plate having ahead of said groove a down-turned lip slidably engaging the top of said cutting blade ahead of its track, said track being interrupted to provide a socket for receiving a cutter-blade-actuating part of said vibrator, said support plate including a generally horizontal wall portion connecting said upstanding wall and the part of the support plate which carries said groove, said horizontal wall portion having an opening, said actuating part extending through said opening into said socket, said opening affording a field of operation for said actuating part.

8. A hair clipper comprising a body, a hood on said body, a vibrator in said hood, a latch part in said hood secured to said body, and a cutting mechanism having a latch part for coacting with said body latch part to removably secure said cutting mechanism to said body, said mechanism latch part including a strip traversing said cutting mechanism, a support plate secured to said mechanism latch part and having a groove, a comb blade pivotally connected to said support plate, and a cutting blade slidably in said groove and resting on the top of said comb blade, said cutting blade having a part coacting with said vibrator for reciprocation of said cutting blade relative to said comb blade, said comb blade having, along two opposite edges, rows of teeth, one row of teeth having more teeth than the other row, said strip having end flanges overlapping the side walls of said body, said strip at opposite ends having upstanding tabs for engaging oppositely located side surfaces at the exterior of said hood when said two latch parts are coupled, said strip being downbent to provide depending projections adjacent the lower ends of said tabs, there being recesses in the upper face of the comb blade for receiving said projections to prevent wobbling of the comb blade.

9. A hair clipper comprising a body, a hood on said body, a vibrator in said hood, a latch part in said hood secured to said body, and a cutting mechanism having a latch part for coacting with said body latch part to removably secure said cutting mechanism to said body, said mechanism latch part including a strip traversing said cutting mechanism, a support plate secured to said mechanism latch part and having a groove, a comb blade pivotally connected to said support plate, a cutting blade slidably in said groove and resting on the top of said comb blade, said cutting blade having a part coacting with said vibrator for reciprocation of said cutting blade relative to said comb blade, said comb blade having, along two opposite edges, rows of teeth, one row of teeth having more teeth than the other row, said strip having end flanges overlapping the side walls of said body, said strip at opposite ends having upstanding tabs for engaging oppositely located side surfaces at the exterior of said hood when said two latch parts are coupled, said strip being downbent to provide depending projections adjacent the lower ends of said tabs, there being recesses in the upper face of the comb blade for receiving said projections to prevent wobbling of the comb blade, said tabs having enlargements near their tops for affording grip surfaces where-
75 by said tabs may be manually lifted to spring

said projections out of the recesses in the upper face of the comb blade to permit reversal of the latter.
